UNITED STATES PATENT OFFICE.

HENRY M. SUTTON, WALTER L. STEELE, AND EDWIN G. STEELE, OF DALLAS, TEXAS.

PROCESS OF AND APPARATUS FOR SIZING COMMINUTED MATERIAL.

1,119,662.

Specification of Letters Patent.

Patented Dec. 1, 1914.

Original application filed July 21, 1913, Serial No. 780,360. Divided and this application filed September 18, 1913. Serial No. 790,496.

To all whom it may concern:

Be it known that we, HENRY M. SUTTON, 5 WALTER L. STEELE, and EDWIN G. STEELE, citizens of the United States, residing at Dallas, in the county of Dallas and State of Texas, have invented certain new and useful Improvements in Processes of and Apparatus for Sizing Comminuted Material, of which the following is a specification, reference being had therein to the accompanying drawing.

This invention relates to certain new and useful improvements in process of and apparatus for sizing or classifying comminuted material according to the size of the particles of the material, regardless of any difference in specific gravity of the particles constituting the comminuted material and comprises a division of our application, Serial 20 Number 780,360 filed July 21, 1913, whereby the particles can be classified according to size and discharged from the apparatus in different receptacles; the particles in each of the receptacles being substantially all of the 25 same size regardless of their difference in specific gravity.

Another object of our invention is to provide a continuously moving roughened sizing surface or deck having a constantly 30 changing inclination away from the point of feed upon which the comminuted material is delivered and from which the particles of the comminuted material are discharged according to their size; means being provided 35 for agitating the sizing surface so as to cause the particles thereon to be agitated, whereby the particles will gravitate at different rates of speed according to their size radially of the sizing surface from which they can be 40 discharged into receptacles.

Another and further object of the invention is to provide an apparatus in which the comminuted material will be prevented from accumulating at the point of delivery upon 45 the sizing surface, thereby overcoming the difficulties now existing with separators of this character, as the agitation of pulverulent material upon a table which is not continually in motion, causes the finer particles thereof to become more thoroughly packed 50 and prevents the mere granular particles from moving in order to properly size the material.

Another and further object of the inven-

tion is to provide a process and apparatus by 55 means of which, a greater amount of material can be sized in a given time than with other classes of sizing machines, and the cost of sizing per ton, is greatly reduced.

Another and further object of the invention is to provide a process and apparatus by means of which, comminuted material having particles differing in size to a great extent, can be classified. That is, large particles as well as pulverulent material from the 65 crusher can be delivered upon the continuously moving sizing surface and when discharged therefrom into the respective receptacles, the particles in one receptacle will be substantially of the same size; that is, particles of material of low specific gravity of a certain size will be deposited with particles of high specific gravity of the same size, and so on throughout the classification. The 70 pulverulent material adhering to the continuously moving surface is discharged after the larger particles have been discharged into a separate receptacle and can be separated if the same contains minerals of value.

A further object of the invention is to provide a process and apparatus for sizing or classifying material in which screens of all kinds are dispensed with, thereby overcoming the difficulties now existing with screen sizers and at the same time, a classifying surface is produced which is not subjected to the sliding action of the material being sized, thereby reducing the frictional wear on the surface, which is the main difficulty with a screen classifier used for screening pulverulent material, as the life of the screen when operating upon certain classes of material is very short and as the cost of the screen has to be considered in connection with the cost of classifying ore, it will be seen that by providing a classifying surface which is not subjected to wear to any extent, the cost of classifying comminuted material is greatly 90 reduced.

We are aware that we are not the first in 100 the art to provide a sizer or classifier in which the particles are classified according to their size by the movement of the particle upon a classifying surface but in apparatuses of this character previously constructed, a classifying surface was given a projecting pulsation in order to cause the particles to be advanced thereon by a sliding action,

while with our apparatus, the agitation of the classifying surface does not affect the movement of the particles longitudinally upon the surface but causes the same by being agitated, to roll by gravity radially of the classifying surface and as the classifying surface is moved continuously, the particles are carried by the moving surface or deck longitudinally, when they are in the act of 5 rolling radially and by timing the speed of movement of the classifying surface and regulating the pitch of the surface so as to cause the particles to travel by gravity at a certain rate of speed, a classifier can be produced which will thoroughly classify the 10 comminuted material delivered thereon at a high rate of speed and at a small cost, which is the main object to be accomplished in all classifiers now in use.

20 A further object of the invention is to provide a roughened or corrugated classifying surface in order to form a resistance on the material without actually obstructing the flow of the particles by gravity radially 25 across the surface, as it is a well-known fact that the larger particles when placed upon an inclined surface will travel at a higher rate of speed than the smaller particles, and our improved process and apparatus is carried out upon this fundamental principle.

30 Other and further objects and advantages of the invention will be hereinafter set forth and the novel features thereof defined by the appended claims.

35 In the drawings—Figure 1, is a side elevation of an apparatus for carrying out the process of sizing or classifying comminuted material, upon a roughened surface having a constantly changing inclination away 40 from the point of feed; and Figs. 2 and 3, are diagrams of the apparatus showing the same arranged upon an oblique axis in order to arrange the conical classifying surface upon an inclination for the purpose of increasing the pitch of the surface away from 45 the point of feed; the diagrammatic lines showing the ratio of the pitch to the size of the material being delivered upon the conical classifying surface. Fig. 4, is a 50 vertical section through the apparatus for carrying out the process of sizing and classifying comminuted material; Figs. 5, 6 and 7 are plan views of conical classifying surfaces showing various forms of corrugations in 55 order to carry out the process of sizing and classifying comminuted material.

60 Like numerals of reference refer to like parts in the several figures of the drawings.

In constructing an apparatus for carrying out our process for classifying comminuted material upon a constantly changing inclined surface, we employ a base 1 having a central bearing 2 in which is mounted an obliquely arranged shaft 3 supported at its upper end by an arm 4 extend-

ing from the base 1 which is provided with a bracket arm 5 in which is mounted a driven shaft 6 provided with a pulley 7 over which the power belt 8 passes.

The shaft 6 is provided with a beveled 70 pinion 9 which meshes with a bevel gear 10 feathered upon the upper end of the shaft 3 as clearly shown. Surrounding the shaft 3 and resting upon the bearing 2, is a collar 11 upon which is mounted a coil spring 12 75 for supporting a conical deck frame 13 provided with a bearing 14 at its upper end to receive the shaft, and said conical frame is provided with a roughened classifying surface deck 15 upon which, the comminuted 80 material is adapted to be delivered from a gate-controlled feed hopper 16 carried by the arm 4.

It will be seen that by arranging the conical roughened classifying surface upon an 85 incline as clearly shown, that the material fed from the hopper upon the same will be progressively subjected to the force of gravity as the surface is revolved so as to increase the force from the point of feed in 90 order to cause the finer or pulverulent material to be discharged from the surface after the larger particles have been discharged therefrom.

In order to cause the conical frame carrying the roughened classifying surface to vibrate when the same is rotated through the medium of the bevel gear and drive pulley, we provide the arm 4 with a ratchet member 17 which co-acts with the companion 100 ratchet member 18 carried by the obliquely arranged shaft 3, the teeth of which are so arranged that when the cone is rotated in the direction of the arrow, the same will be pushed downwardly against the tension of 105 the spring as the teeth ride over one another and the surface will be constantly vibrated so as to cause the comminuted material delivered upon the classifying surface to move radially.

110 While we have shown and described a particular form of mechanism for vibrating the classifying surface, it is of course understood that various other forms of mechanisms could be employed to accomplish this 115 result and we do not wish to limit ourselves to any particular mechanism for causing the classifying surface to vibrate when it is being rotated. It is also of course understood that various other driving mechanism 120 can be employed and while we have shown a top drive in connection with this form of apparatus for carrying out our improved process of classifying comminuted material, we do not wish to limit ourselves to any 125 exact construction of apparatus, as the fundamental principle of the invention is to provide a conical classifying surface with a constantly changing inclination in order to progressively increase the pitch of inclina- 130

tion of the surface away from the point of feed so as to increase the effect of the force of gravity upon the comminuted material on the surface from the point of feed.

- 5 The base 1 is provided with radial arms 19 carrying a circular apron 20 above which is arranged a circular bar 21 for holding the spacing or separating fingers 22 in their adjusted position in order to size the material into various sizes as the same is discharged radially from the conical separating surface. While we have shown this particular form of apron used in connection with a conical classifying surface, it is of course understood that suitable receptacles, not shown can be arranged to receive the material discharged therefrom without departing from the spirit of our invention and we do not wish to limit ourselves to any particular form of collecting means to be used in connection with this invention.

In order to clearly illustrate the travel of the particles of comminuted material upon a constantly increasing inclined classifying surface, the diagrammatic views as shown in Figs. 2 and 3 are presented in which the cone is inclined for the purpose of increasing the pitch or inclination of a surface away from the point of feed of the comminuted material and in these figures, 94 indicates the feed hopper; 16 and 3 the obliquely arranged supporting shaft of the cone; a vertical line being indicated by 152. The diagrammatic lines show the ratio of this pitch to the size of the material on the cone and taking line 151 as the base line in connection with the vertical line 152, the line 142 shows the degree of slope of the cone at the feed. As the material gets finer, the slope of the cone by its inclination gets deeper until we reach the line 150 which represents the point when the finer particles of the material are delivered from the surface. This increases the pitch of the cone and facilitates the delivery of the finer comminuted material and as in all other cases, the shading upon these figures shows the travel of the material upon the cone when the cone is revolving and being agitated.

50 In Figs. 5 to 7, we show various forms of classifying surfaces 100 for the conical apparatus in which the corrugations or roughened surfaces are arranged so as to accommodate different grades of material and while we have shown these forms as preferred types of surfaces, we do not wish to limit ourselves, as other forms of corrugations running in different directions can be used without departing from the spirit of our invention.

While we have shown and described a particular form of apparatus for carrying out the process of sizing or classifying comminuted material according to the size of the particles regardless of the specific gravity

thereof, we wish it to be clearly understood that various other forms of apparatus can be used for carrying out our improved process without departing from the spirit of our invention as the fundamental principles 70 of this invention are a continuously moving inclined roughened surface upon which comminuted material is delivered and carried by the moving surface away from the point of feed; the surface being agitated so as to cause the particles to travel transversely of the moving surface by gravity upon the inclined surface according to their size, whereby all of the particles of the comminuted material will be sized and classified which 80 are of any size and are affected by gravity, the pulverulent material being discharged from the surface separately from the particles of any size.

We claim:

1. The process of sizing comminuted material, containing particles of different sizes, consisting in continuously moving and agitating said material when in dry condition, subjecting said material to the force of 90 gravity to cause said material to move in lines deviating from the continuous movement of said material at angles proportionate to their sizes, varying the force resisting the responsiveness of the particles to the force of gravity, exerting a resistance on said material against the force of gravity, and separately collecting the thus sized particles.

2. The process of sizing comminuted material, containing particles of different sizes, consisting in continuously moving and agitating said material when in dry condition, subjecting said material to the force of gravity to cause said material to move in lines 100 deviating from the continuous movement of said material at angles proportionate to their sizes, gradually decreasing the force resisting the responsiveness of the particles to the force of gravity, exerting a resistance 105 on said material against the force of gravity, and separately collecting the thus sized particles.

3. The process of sizing a mass of comminuted material, consisting in subjecting 115 a mass of material containing particles of different sizes in dry condition, to a continuous movement in one direction upon a moving support, causing the particles to gravitally deviate from the line of normal movement, varying the force resisting the responsiveness of the particles to the force of gravity, retarding said gravitational deviation and so proportioning the forces that the deviation 120 shall be proportional to the size of the respective particles, and separately collecting 125 the thus sized particles.

4. The process of sizing a mass of comminuted material, consisting in subjecting a mass of material containing particles of dif- 130

- ferent sizes in dry condition, to a continuous movement in one direction upon a continuously moving support, causing the particles to gravitally deviate from the line of normal movement of the material, varying the force resisting the responsiveness of the particles to the force of gravity, retarding said gravitational deviation causing the particles to travel contiguously, and so proportioning the forces that the deviation shall be proportional to the size of the respective particles, and separately collecting the thus sized particles.
5. The process of sizing a mass of material, consisting in continuously moving said material in one direction, agitating said material, subjecting said material to the force of gravity at an angle to the continuous movement of the material, varying the force resisting the responsiveness of the particles to the force of gravity, causing the different components of the mass to travel contiguously according to the size of the particles thereof at different rates of speed, in lines deviating from the line of continuous movement of said material, and separately collecting the thus sized particles.
6. The process of sizing a mass of comminuted material, consisting in continuously moving the mass of material away from the point of feed in one direction, subjecting the mass to the force of gravity, varying the force resisting the responsiveness of the particles to the force of gravity, exerting a resistance to the mass of particles in their movement by gravity causing the unpulverized particles to travel contiguously in lines deviating from the line of normal movement of the pulverulent material at angles proportionate to their sizes, and separately collecting the so sized particles.
7. The process of sizing a mass of material, consisting in feeding said material to a continuously moving supporting surface, subjecting said material to the force of gravity when on said surface, varying the force resisting the responsiveness of the particles to the force of gravity, agitating said material upon said surface, exerting a deflecting resistance to said material on said support against the force of gravity to cause the components of said material to travel at angles to the continuous movement against the resistance, the resistance and components of motion due to gravity, being proportioned to the size of the particles, and separately collecting the thus sized particles.
8. The process of sizing a mass of comminuted material, consisting in feeding said material onto a continuously moving supporting surface having a surface constantly changing in inclination to subject the mass of particles thereon to the force of gravity, gradually increasing in force from the point of feed, agitating said material upon said surface, exerting a resistance to said material on said support against the force of gravity, to cause the components of said material to travel at angles to the continuous movement against the resistance, the resistance and components of motion due to gravity, being proportioned to the size of the particles, and separately collecting the thus sized particles.
9. The process of sizing a mass of pulverulent material, consisting in feeding the material dry upon a continuously moving roughened supporting surface having a constantly changing inclination, agitating said supporting surface and causing the components of said mass to deviate from the line of normal movement at angles proportionate to their sizes, and separately collecting the thus sized particles.
10. The process of sizing a mass of comminuted material, consisting in feeding said material when in dry condition upon an inclined continuously moving surface having a constantly changing inclination, progressively subjecting said material upon said surface to the force of gravity, reducing the force resisting the responsiveness of the particles to the force of gravity from the point of feed, agitating said particles when upon said surface, to cause the particles to gravitate thereon, exerting a resistance to said particles upon said surface in their movement by gravity, and separately collecting the thus sized particles.
11. The process of sizing a mass of material, consisting in feeding said material onto a continuously moving supporting surface, subjecting said material to the force of gravity when on said surface, gradually decreasing the force resisting the responsiveness of the particles to the force of gravity, agitating said material upon said surface, exerting a deflecting resistance to said material on said surface against the force of gravity, and separately collecting the thus sized particles.
12. The process of sizing a mass of material, consisting in feeding said material upon an inclined continuously moving roughened surface, agitating said material upon said surface to aid the movement of said material by gravity, gradually decreasing the force resisting the responsiveness of the particles to the force of gravity, and causing the granular particles thereof to move in lines deviating proportionately to their sizes, from the line of movement of the material, and separately collecting the thus sized particles and the pulverulent material.
13. In a machine for sizing solid material, a longitudinally progressing imperforated separating surface having a constantly changing inclination, mechanism for imparting agitative movement thereto, means

to feed unsized material to said surface; and means to collect the different grades of sized material discharged from said surface.

14. In a machine for sizing solid material, 5 a laterally inclined and longitudinally progressing imperforated separating surface having a constantly changing inclination away from the point of feed, mechanism for imparting agitative movement thereto, 10 means to feed unsized material to said surface, and means to collect the different grades of sized material discharged from said surface.

15. In a machine for sizing solid material, 15 a laterally inclined and longitudinally progressing imperforated separating surface, mechanism for imparting agitative movement thereto, to cause the particles to gravitate thereon, means for varying the force 20 resisting the responsiveness of the particles to the force of gravity, means to feed unsized material to said surface, and means to collect the different grades of sized material discharged from said surface.

16. In a machine for sizing solid material, 25 a laterally inclined and longitudinally progressing separating surface, means to feed unsized material to said surface, mechanism for imparting agitative movement thereto, 30 to cause the particles to gravitate thereon, means for gradually decreasing the force resisting the responsiveness of the particles to the force of gravity, and means to collect the different grades of sized material 35 discharged from said surface.

17. In a machine for sizing solid material, 40 an obliquely arranged conical classifying surface having an outwardly inclined surface, means for feeding unsized material to 45 said surface, means for continuously revolving said surface in one direction, means for agitating said surface to cause the particles of said mass to gravitate toward the base of said surface, and means to collect the different grades of sized material discharged from 50 said surface.

18. A machine for sizing solid material, 55 comprising a base, a shaft extending obliquely from said base, a support for the upper end of said shaft, a frame carried by said shaft, a roughened classifying surface mounted upon said frame having an outwardly inclined surface, means to feed unsized material to said surface adjacent the upper portion of said surface, means for driving said shaft continuously in one direction, means for agitating said classifying surface to cause the particles to gravitate thereon, and means for separately collecting the different grades of sized material discharged from the outer edge of said surface.

19. A machine for sizing solid material, 60 comprising a base having a shaft extending obliquely therefrom, a support for the upper end of said shaft, a ratchet carried by said

support, a classifying surface carried by said shaft having an outwardly inclined surface, a ratchet carried by said shaft coöperating with the first-mentioned ratchet, means for revolving said shaft, means for feeding 70 unsized material to said surface adjacent the shaft, and means to collect the different grades of sized material discharged from said surface.

20. In a machine for sizing solid material, 75 the combination with a base having an arm extending therefrom, of an inclined shaft revolvably mounted upon said base supported by said arm, driving mechanism for said shaft, agitating mechanism for said shaft, 80 a conical classifying surface carried by said shaft having an outwardly inclined roughened surface, means to feed unsized material to said surface, and means for collecting the different grades of sized material 85 discharged from the outer edge of said surface.

21. A machine for sizing solid material, comprising a base, an obliquely arranged spring-supported shaft mounted in said 90 base, a support for the upper end of said shaft, a ratchet carried by said support, a ratchet carried by said shaft coöperating with the first-mentioned ratchet, means for driving said shaft continuously in one direction, 95 a conical classifying surface mounted upon said shaft having an outwardly inclined surface, a hopper arranged to deliver comminuted material upon said classifying surface adjacent the point thereof, and 100 means to collect the different grades of sized material discharged from said surface.

22. A machine for sizing solid material, comprising a base having a bearing, a shaft mounted in said bearing and extending 105 obliquely therefrom, a conical classifying surface carried by said shaft having an outwardly inclined surface, means for feeding unsized material to said surface adjacent the point thereof, means for agitating said surface, 110 means for exerting a resistance to said material in its movement by gravity, means for revolving said classifying surface, and means for separately collecting the different grades of sized material discharged from 115 said surface.

23. In a machine for sizing solid material, the combination with a conical classifying surface mounted upon an obliquely arranged axis, means for revolving said classifying 120 surface to constantly change the inclination thereof, means for agitating said surface, a hopper arranged to deliver comminuted material upon said surface at a point opposite to the point of greatest inclination, and 125 means to collect the different grades of sized material discharged from said surface.

24. In a machine for sizing solid material, the combination with a base having a bearing, a shaft mounted in said bearing and ex- 130

- 6
24. Tending obliquely therefrom, a frame fixed on said shaft, a conical roughened classifying surface mounted upon said frame having an outwardly inclined surface, a hopper for delivering comminuted material in unsized condition upon said surface, means for rotating said surface, means for agitating said surface during its rotation, and means to collect the different grades of sized material discharged from said surface.
25. In a sizing apparatus, the combination with a continuously moving transversely inclined progressing separating surface, of means for feeding material upon said surface adjacent its upper edge, means for varying the force resisting the responsiveness of the particles to the force of gravity, means for exerting a resistance to said material in its movement by gravity adapted to retard the material without stopping the same in its movement by gravity, means for vibrating said supporting surface to modify said resistance, and means for collecting the sized particles.
26. An apparatus for sizing comminuted material, comprising a laterally inclined and longitudinally progressing separating surface, provided with resistance means arranged at an angle to the inclination thereof adapted to retard without stopping the movement of the dry pulverulent material by gravity, means for varying the force resisting the responsiveness of the particles to the force of gravity, means for vibrating said surface, and means for collecting the
27. An apparatus for sizing comminuted material, consisting of particles of different sizes, comprising a laterally inclined and longitudinally progressing separating surface, means for varying the force resisting the responsiveness of the particles to the force of gravity in the continuous movement of said surface, said surface having a roughened sizing surface for exerting a resistance to the dry material adapted to retard without stopping, the movement of the material in its movement by gravity, means for vibrating said surface to modify the resistance, and means for separately collecting the different grades of sized material discharged from said surface.
28. In a machine for sizing solid material, a laterally inclined and longitudinally progressing separating surface, provided with a progressively increasing inclination away from the point of feed, mechanism for imparting agitative movement thereto, and means to collect the different grades of sized material discharged from said surface.

In testimony whereof we affix our signatures in presence of two witnesses.
